UNITED STATES PATENT OFFICE

107,641

DESIGN FOR AN INTERNAL COMBUSTION ENGINE

John L. Doll and Clifford W. Rogers, Detroit, Mich., assignors to Syncro Devices, Incorporated, Detroit, Mich., a corporation of Michigan

Application July 6, 1937, Serial No. 70,279

Term of patent 3½ years

To all whom it may concern:

Be it known that we, John L. Doll and Clifford W. Rogers, citizens of the United States, residing at Detroit, in the county of Wayne and State of Michigan, have invented a new, original, and ornamental Design for Internal Combustion Engines, of which the following is a specification, reference being had to the accompanying drawing, forming part thereof, wherein:

Fig. 1 is a top plan view of the internal combustion engine showing our new design.

Fig. 2 is a side elevational view thereof.

Fig. 3 is a rear end elevational view.

We claim:

The ornamental design for an internal combustion engine, as shown.

JOHN L. DOLL.

CLIFFORD W. ROGERS.
